(57) **CLAIM**

The ornamental design for trousers as shown and described.

DESCRIPTION

FIG. 1 is a front perspective view of trousers showing my new design;

FIG. 2 is a front view thereof; and,

FIG. 3 is an enlarged view of the encircled portion in FIG 2. The broken lines are shown to disclose the environment of use and to define boundaries in FIGS. 1 and 3. These broken lines form no part of the claimed design.

The dash broken lines shown in the drawings depict portions of the trousers and pockets snaps that forms no part of the claimed design. The line-dash-dash lines in the drawings represent the boundaries of the enlargement and form no part of the claimed design. The small sized dash broken lines in the pockets depict stitching that form no part of the claimed design.

1 Claim, 3 Drawing Sheets

FIG. 1

FIG. 2

FIG. 3
